UNITED STATES PATENT OFFICE.

WILLIAM E. SAUERMAN, OF BELMOND, IOWA.

HANGER FOR HATS AND OTHER ARTICLES.

1,257,406.

Specification of Letters Patent. Patented Feb. 26, 1918.

Application filed May 21, 1917. Serial No. 170,088.

To all whom it may concern:

Be it known that I, WILLIAM E. SAUERMAN, a citizen of the United States of America, and resident of Belmond, in the county 5 of Wright and State of Iowa, have invented a new and useful Hanger for Hats and other Articles, of which the following is a specification.

The object of this invention is to provide 10 an improved construction for hangers.

A further object of this invention is to provide means for suspending a hat, dish-cloth, towel or other article in a convenient manner and by such an arrangement that 15 the article may readily be withdrawn or disconnected from the suspending means by a manual jerk or pull of the article.

A further object of this invention is to provide means for suspending an article, 20 such as a hat or towel, by spring pressure which may be released by a slight jerk or pull manually on the suspended article.

A further object of this invention is to provide a portable article, easily carried 25 about or packed in a grip, and adapted to be suspended on a nail or hook, which article includes spring pressure and is adapted to grip and suspend another article, such as a 30 hat or towel, in such manner that the latter article may be removed from the former article readily and conveniently by a slight jerk or pull manually applied thereto.

My invention consists in the construction, arrangement and combination of elements 35 hereinafter set forth, pointed out in my claims and illustrated by the accompanying drawings, in which—

Figure 1 is a face elevation of my improved device, a suspended article being 40 shown by dotted lines associated therewith. Fig. 2 is a side elevation of the same device. Fig. 3 is a side elevation of a slightly modified form of device.

In the construction of the device as shown 45 the numeral 10 designates a base plate, which is formed with a hole 11 in the central portion of one end adapted to receive a nail or hook, not shown, whereby said plate may be mounted for use, such as on 50 the wall of a room. The base plate 10 preferably is formed with a notch 12 opening to one end and end portions of the arms so formed are beveled in front and on their outer sides as at 13, 14. A wire yoke 15 is 55 mounted across the central portion of the notch 12 and the arms of the yoke are ex-

tended through holes in the arms of the base plate and are clenched on the back of said plate. A roller 16 is pivoted on the central portion of the yoke 15 and lies partially 60 within the notch 12 and partially in front of the plane of the base plate. A spring-wire frame or clip is formed of a single length of wire, generally U-shaped in plan or face view, and the body or yoke 17 there- 65 of overlies the face of the plate 10, the arms extending on or near the median lines of the arms of the plate and the head crossing the outer end of the notch 12. Spring-coils 18, 19 are formed in, and oppositely relative to 70 each other, the end portions of the frame, and said coils register transversely of and contact with the outer face of the plate 10 contiguous to the notch 12. End portions 20 of the spring-wire frame or clip (one of 75 which is shown in Fig. 2) are extended through holes in the base plate 10 and are clenched on the back of said plate. The yoke portion 17 of the spring-wire frame or clip may be arched or offset in any de- 80 sired form or manner relative to the faces of the base plate and relative to the periphery of the roller 16.

In practical use an article, such as a hat (shown by dotted lines in Fig. 1), dish-cloth, towel or garment, may be pushed or drawn between the yoke member 17 on one side and the plate 10 and roller 16 on the other side, and when so placed said article will be held by gripping action of said yoke 85 member and may be suspended by hanging the plate as described. The article may be removed by a slight jerk or pull manually applied thereto, the article withdrawing over the roller 16 and rotating said roller 90 in such movement. In such manner the roller 16 minimizes friction on the article and prevents tearing or undue wear thereof. This function of the roller also is exercised 95 in placing the article in suspending relation 100 with the hanger.

The hanger may be carried about, mounted wherever desired and used promiscuously at the will of the operator.

In Fig. 3 I have shown a slightly modified form of the device, in which the base plate 10^a is formed of sheet metal by stamping, bending or pressing. The lower portion of the base plate 10^a preferably is bent or curved rearwardly as at 13^a, and the 110 lower end of the yoke 17^a may be bent or curved forwardly as at 17^b, to provide a

wedge-shaped entrance space and facilitate engaging an article to be suspended in the device.

I do not desire to be understood as limiting myself to the precise construction illustrated and described as the same may be modified without departing from my invention.

I claim as my invention—

- 10 1. A hanger for hats and other articles formed with a base plate having a hole in one end and a roller-opening spaced from said hole, a yoke formed of a single length of wire and substantially U-shaped, which 15 yoke is mounted with its closed central portion extending across said opening and having its arms extending through and clenched on the back of said plate, there being a roller pivoted on said yoke and extending 20 within the opening in said plate, there being a spring-wire clip spaced from said plate and extending in embracing relations with said roller, said clip being formed of a single length of wire and substantially 25 U-shaped, the closed central portion of said clip extending across said plate, there being spring coils formed in the arms of said clip and contacting with said plate, end portions of the arms of said clip being extended 30 through and clenched on the back of said plate, there being a wedge-shaped entrance space between the closed end of the clip and the plate.

2. A hanger for hats and other articles

formed with a base plate, a yoke mounted 35 on said plate, a roller pivoted on said yoke, and a spring-wire clip associated therewith, said clip being formed of a single length of wire and substantially U-shaped, the closed central portion of said clip extending trans- 40 versely of the plate parallel with the axis of the roller, there being spring coils formed in the arms of said clip and contacting with said plate, end portions of the arms of said clip being extended through and 45 clenched on the back of the plate.

3. A hanger for hats and other articles formed with a base plate generally rectangular and relatively thin and broad, which 50 plate is formed with a hole in one end and a notch opening to its other end and extending across the center thereof, there being a yoke mounted across said notch and having the ends of its arms extending through and clenched on the back of said 55 plate, there being a roller pivoted on said yoke and extending within the notch of the plate, together with a spring clip separately formed and fixed to said plate in operative relation with the roller and plate. 60

4. A hanger for hats and other articles, comprising a base plate, a roller pivoted to and extending through said plate, and a spring clip associated therewith, said plate and spring clip being formed with end portions diverging relative to each other. 65

WILLIAM E. SAUERMAN.
